(57) **CLAIM**

The ornamental design for a novelty bottle opener, as shown and described.

DESCRIPTION

FIG. 1 is a perspective view of a novelty bottle opener showing my new design;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof; and,

FIG. 8 is a perspective view of a novelty bottle opener shown in a condition of use thereof.

Broken lines shown in the drawings are for the purpose of illustrating portions of the novelty bottle opener, which form no part of the claimed design.

The human hand and bottle shown in broken lines in FIG. 8 are for the purposes of illustrating environmental structure, which form no part of the claimed design.
